METHOD AND MEANS FOR MEASURING SLIVER PRODUCTION

Charles D. Forney, Jr., Lawndale, N.C.

Application February 9, 1956, Serial No. 564,534

6 Claims. (Cl. 19—159)

This invention relates to textile sliver producing machinery such as carding machines, comber machines and other machines wherein a sliver is delivered into a container, such as a can, or onto a roll by a coiler mechanism, and it is an object of this invention to provide a novel method and means for accurately determining the production of sliver producing machines of the character described by passing the sliver in engagement with a counter-operating rotatable element which is driven by contact with the moving sliver as the sliver is introduced into the coiler head of a coiler mechanism.

It is another object of this invention to provide means on the coiler head for resiliently supporting a recording counter whose counting mechanism is coupled to a shaft on which a wheel or roller is secured and whereby the wheel or roller rests lightly upon the sliver in its course over the casing of the coiler head whereby any abnormally thickened places or hard places in the sliver will elevate the wheel and the recording counter as such thick or hard places pass beneath the wheel.

It is still another object of this invention to provide apparatus of the character described wherein means are provided for vertically adjusting the position of the recording counter and, consequently, the wheel, to accurately determine the displacement between the lower surface of the wheel and the upper surface of the casing of the coiler head whereby the position of the wheel may be so adjusted that undesirable relatively thin places in the sliver will not rotate the counter wheel. Since the attendants of sliver producing machinery are generally paid on the basis of the actual length of the slivers produced, this would be an incentive for the attendants to be on the alert for the occurrence of relatively thin places in the slivers so the necessary corrections of the adjustments or operations of the corresponding machine would be made promptly, thereby resulting in a better grade or quality of sliver than would be the case in the event that the improved measuring device was not used.

Some of the objects of the invention having been stated, other objects will appear as the description proceeds when taken in connection with the accompanying drawing, in which—

Figure 1 is a fragmentary view of a sliver producing machine embodied in a carding machine, showing the sliver as it is directed to a coiling mechanism with the improved sliver measuring device mounted upon the casing of the coiler head, some of the parts being broken away and others being shown in section for purposes of clarity;

Figure 2 is an enlarged fragmentary elevation looking along line 2—2 in Figure 1, but omitting the sliver;

Figure 3 is an enlarged fragmentary plan view taken substantially along line 3—3 in Figure 2;

Figure 4 is a fragmentary vertical sectional view taken substantially along line 4—4 in Figure 3.

Referring more specifically to the drawing, the doffer or discharge end of a carding machine 10 is shown in Figure 1, the carding machine being a preferred embodiment

2

ment of a sliver producing machine. The carding machine 10 includes the usual doffer cylinder 11 from which a fibrous web W is removed by a conventional oscillating knife 13. The web W is drawn through a conventional trumpet 14 and condensed into a sliver S by means of a pair of driven calender rolls 15, 16.

From the calender rolls 15, 16 the sliver S passes upwardly and over a guide 17 provided on the cover or casing 20 of a coiler head 21 which is a usual part of a coiler mechanism. The upper wall of the casing or cover 20 has a conventional trumpet 22 positioned therein forwardly of the guide 17 which condenses the sliver as it is drawn therethrough by a pair of coiler calender rolls 23. The calender rolls 23 direct the sliver S into an inclined passageway or tube 24 of a conventional tube wheel or tube gear 25 which is driven in a conventional manner.

The coiler head 21 is supported on the usual pedestal 26 whose lower end rests upon the floor upon which the machine 10 rests and has a plate 27 projecting therefrom having usual means therein for rotating a coiler plate 30 upon which a can 31 rests. Of course, the sliver S is coiled into the can 31 by the tube gear 25 in a well known manner.

The parts heretofore described are conventional and their operation is well known in the art and, accordingly, a further description thereof is deemed unnecessary.

The means for carrying out the novel method for measuring sliver as it is produced comprises a registering counter 35 of the usual type such as manufactured by Veeder-Root, Inc., 25 Sargeant Street, Hartford, Conn. The registering counter 35 is of the usual type having a window 36 therein through which counter wheels 37 may be observed and which counter wheels 37 may be reset by conventional means including a reset handle 40. The counter wheels 37 may indicate any desired type of lineal measure, but are preferably arranged to indicate the number of hanks of roving or sliver S produced.

The registering counter 35 includes a shaft 41 extending substantially horizontally therefrom on which a wheel or roller 42 is suitably secured, the wheel 42 overlying the cover or casing 20 of the coiler head 21 at a point intermediate the guide 17 and the trumpet 22. A substantially U-shaped trough member 43 is preferably provided below the wheel 42 to assist in maintaining the sliver S in alignment with the wheel 42 as the sliver passes between the guide 17 and the trumpet 22 on the cover 20 of the coiler head 21. The periphery of the wheel 42 may be irregular, concave or convex, but is preferably flat as shown in the drawing. It should be noted that the proximity of the wheel 42 to the trumpet 22 is such that the fibers in the sliver S are compressed or condensed somewhat so that any additional friction created at this point by engagement of the wheel 42 with the sliver S will not cause the sliver to break, as it would if the wheel 42 contacted the sliver S at a point too remote from the trumpet.

The registering counter 35 is suitably secured, as by bolts 45, to the upper surface of a hinged or vertically adjustable plate 46, the plate 46 preferably being provided with elongated slots 47 for the bolts 45 to facilitate adjustment of the counter 35 so the wheel 42 may be properly aligned with the trough 43. The rear end of the plate 46; that is, the end thereof nearest the direction from which the sliver S is moving, is pivotally or hinged connected as at 48 to the rear end of the upper portion or platform 50 of a resilient support broadly designated at 51. The resilient support 51 is shown in the form of a leaf spring member and the forward end of the platform curves downwardly and beneath itself to form a relatively short bottom portion 52 which is

suitably secured, as by screws 54 to the upper surface of the cover or casing 20 of the coiler head 21.

The support 51 is preferably made from a resilient or flexible material such as spring steel and it will be observed in Figures 3 and 4 that the support is disposed to one side of the path of travel of the sliver in its course from the guide 17 to the trumpet 22. It is thus seen that the platform 50 of the support 51 is biased downwardly by the weight of the registering counter 35, its shaft 41 and the wheel 42 so the wheel 42 rests 10 lightly and resiliently upon the sliver S as it passes between the guides 17 and trumpet 22.

Now, it occasionally happens that relatively thin places are present in the sliver S which thin places are of insufficient thickness or density to be counted as a fractional part of the unit of length registered on the registering counter 35 relative to the length of such relatively thin portions or places. This condition generally exists when a length of sliver S is initially threaded from the calendar rolls 15, 16 into the coiling mechanism and it is apparent that the attendant of the sliver producing machine should not be credited with having produced sliver of the desired size to constitute hanks or other form of lineal measurement, such as would be indicated by the recording counter 35, during such times that the corresponding lengths of the sliver S are of a size, thickness or density below a given standard.

Accordingly, means are provided for vertically adjusting the registering counter and its actuating wheel 42 relative to the trough 43 and the cover or casing 20 of the coiler head 21 which means also compensates for any variation which might exist in the resiliency of different supports 51. To this end, the forward portion of the hinged or pivoted plate 46 is threadably penetrated by an adjustment screw or set screw 56 whose lower end bears against the platform 50 and which has a lock nut 57 threaded thereon for securing the set screw 56 in the desired adjusted position. It is thus seen that, regardless of the flexibility or resiliency of the support 51, as long as the weight of the recording counter 35 and associated parts is sufficient to bias the platform 50 downwardly, the displacement between the proximal surfaces of the wheel 42 and the trough 43 may be accurately adjusted.

Although the support 51 is described herein as preferably being made from a flexible material, it is contemplated that the support 51 or a similar support may be made from a rigid material, since the set screw 56 may be so adjusted to accurately determine the displacement between the lower surface of the wheel 42 and the upper surface of the cover 20 so that only that portion of the sliver which is of a predetermined minimum thickness will engage and impart rotation to the wheel 42.

It is thus seen that I have provided a novel method of measuring the actual length of sliver having a density or thickness of a predetermined standard including moving the sliver, when of proper thickness, in engagement with a wheel connected to a counting device immediately in advance of the sliver entering the coiling mechanism whereas, heretofore, the only way in which sliver lengths could be measured, to my knowledge, was to provide a counting means of some description which would be driven by the calender rolls, such as the calender rolls 15, 16. It is apparent that, since such calender rolls as the rolls 15, 16 are driven continuously with operation of the sliver producing machine or carding machine 10, such counting devices driven thereby would also indicate length when there actually was no sliver passing therebetween, or the sliver may have been of a thickness or density below the desired standard.

In the drawing and specification there has been set forth a preferred embodiment of the invention and, although specific terms are employed, they are used in a generic and descriptive sense only and not for purposes

of limitation, the scope of the invention being defined in the claims.

I claim:

1. A method of measuring sliver as it is produced on a sliver producing machine which includes moving the sliver between a stationary member and a rotating wheel while condensing the sliver and driving the wheel by engagement of the wheel with the sliver and while maintaining the wheel in such spaced relation to the stationary member that the wheel is driven only by portions of the sliver which are of a predetermined minimum density and thickness when so condensed, and recording the amount of movement of the periphery of the wheel in a given lineal gradation proportionate to the circumference of the wheel.
2. A method of measuring length of sliver produced as it is drawn into a coiler mechanism which includes condensing the sliver while moving the sliver in engagement with the cover of the coiler mechanism and in engagement with a wheel to cause the sliver to drive said wheel and while maintaining the wheel in such spaced relation to the cover that the wheel is driven only by portions of the sliver which are of a predetermined minimum density and thickness when so condensed, and recording the revolutions of said wheel in such proportions as to indicate the length of sliver moving past said wheel.
3. In a sliver producing machine having a device for taking up the sliver as it is produced, said device having a flat surface thereon in engagement with which the sliver is moved as it is taken up; the combination of a wheel biased into engagement with said sliver as it passes in engagement with said flat surface, means for adjusting the displacement between the proximal surfaces of the wheel and said flat surface whereby the wheel will be rotated only by sliver of a predetermined thickness passing between the wheel and the flat surface, and a counter coupled to said wheel for registering the length of the sliver which passes in engagement with and imparts rotation to the wheel.
4. Apparatus for measuring the length of textile sliver as it enters a coiling mechanism wherein the coiling mechanism is provided with a flat substantially horizontal upper surface across which the sliver is drawn in its course into the coiler head, said apparatus comprising a substantially C-shaped support made from a flexible material and having its lower portion fixed to said flat upper surface, a registering counter carried by the upper portion of said support and having an operating shaft extending therefrom and overlying the path of movement of said sliver, a roller fixed on said shaft and engageable by the sliver, and the combined weight of the counter, shaft and roller serving to bias the roller toward the flat surface, and the flexibility of the upper portion of said support being such as to substantially overcome said combined weight, as the weight biases said roller toward said surface, to where the roller is maintained in spaced relation above said surface and is supported independently of the sliver whereby the sliver rotates said roller to register the length of said sliver on the registering counter.
5. Apparatus for measuring the length of textile sliver as it enters a coiling mechanism wherein the coiling mechanism is provided with a flat substantially horizontal upper surface across which the sliver is drawn in its course into a coiler head; said apparatus comprising a substantially C-shaped support made from a flexible material and having its lower portion fixed to said flat upper surface, a plate pivotally connected to the upper portion of said support, a registering counter attached to said plate, said counter having an operating shaft extending therefrom and overlying the path of movement of said sliver, a roller fixed on said shaft and engageable by the sliver, the combined weight of the counter, shaft and roller serving to bias the roller toward the flat surface, and means for adjusting said plate about its pivot

relative to the upper portion of said support to thereby adjust the displacement between the proximal surfaces of the roller and said flat surface of the coiling mechanism, whereby the sliver rotates said roller to register the length of sliver on the registering counter.

6. Apparatus for measuring the length of textile sliver as it enters a coiling mechanism wherein the coiling mechanism is provided with a flat substantially horizontal upper surface across which the sliver is drawn in its course into a coiler head; said apparatus comprising a substantially C-shaped support made from a flexible material and having its lower portion fixed to said flat upper surface, a plate carried by the upper portion of said support, a registering counter secured to said plate, said registering counter having an operating shaft extending therefrom and overlying the path of movement of said sliver, a roller fixed on said shaft and engageable by the sliver, the combined weight of the counter, shaft and

roller serving to bias the roller toward the flat surface whereby the sliver rotates said roller to register the length of said sliver on the registering counter, and means for vertically adjusting the plate relative to the upper portion of the said support for adjusting the displacement between the proximal surfaces of the roller and the flat upper surface of the coiler mechanism.
